LIQUID FUEL BURNING APPARATUS

John Graves McKean, Mount Vernon, and Robert
Frederick Jones, Glasgow, ScotlandApplication June 25, 1934, Serial No. 732,368
In Great Britain July 14, 1933

2 Claims. (Cl. 299—143)

This invention relates to atomizers for liquid fuel burning apparatus of the type comprising a body member formed with a bore presenting a liquid fuel passage, and has for an object to provide an improved atomizer which is operable, satisfactorily by low, medium or high pressure fluid, either compressed air or steam.

According to the invention an atomizer of the above specified type for liquid fuel and the like comprises a tubular body member, a nozzle member having an axial truncated conical passage, an atomizer tip member constituted by a disc having a tubular truncated cone which projects axially from said disc and is positioned within the passage of the nozzle member so as to present an annular discharge passage around said cone, an annular chamber behind said disc, a passage in the body member for conducting atomizing pressure fluid to said annular chamber, inclined holes, circular in cross section, formed through the disc, the inclination of the holes being the same as the inclination of the truncated cone whereby atomizing pressure fluid is passed from the annular chamber behind the disc through the space around the cone without radial deflection.

The holes in the disc of the atomizer tip member may be inclined to correspond substantially to the inclination of the truncated conical projection and the said holes may be angled and inclined to impart to the fluid passing through the nozzle a whirling movement or, alternatively the said holes may be angled in opposite directions and inclined at an angle to the axial center line of the nozzle.

Fig. 1 of the accompanying drawing is a longitudinal section of an atomizer according to an embodiment of the invention. Fig. 2 is a transverse section taken on the line 2—2 of Fig. 1.

According to the invention an atomizer, for liquid fuel burning apparatus, includes a body member 1 formed with bores or passages 2, 2' and 3, 3' which extend longitudinally thereof. The inlet end 4 of the bore or passage 3, 3' of the member 1 is connected to a liquid fuel supply by means of a pipe and coupling and at the same end of the member 1 the inlet end 5 of the bore or passage 2, 2' is connected to an atomizing pressure fluid supply, either compressed air or steam. The end face of the member 1, remote from the connections 4 and 5 to the liquid fuel and atomizing fluid supplies, is formed with a recess 6. The adjacent end, which is the exit end, of the bore 3, 3' opens into the said recess 6 at the center thereof. Conveniently to simplify

manufacture, at a point 7 spaced a relatively short distance from the exit end, the bore 3, 3' is enlarged, the enlarged portion 3, which forms the major part of the bore, being eccentric to the axial or center line of the member 1 and the smaller and exit end portion 3' of the bore being concentric with the axial or center line of the member 1.

In the wall of the member 1, at the exit end thereof and in the bottom or end wall of the recess 6, an annular recess 9 is formed which presents an annular chamber surrounding the exit end 3' of the bore 3, 3'. The adjacent end 2' of the passage 2, 2' opens into the said annular recess or chamber 9. Conveniently to simplify manufacture, at a point 10 spaced a relatively short distance from the exit end, the passage 2, 2' is enlarged, the enlarged portion 2 which forms the major part of said passage, being eccentric to the smaller and exit end part 20 of said passage.

Into the recess 6 an atomizer tip member is fitted. The said tip is constituted by a disc member 11 having a truncated cone 12 projecting from one side thereof. The disc member 11 is placed in the recess 6 so that the truncated cone 12 projects outwardly and is held in position by a nozzle member 13 screw-threaded for engagement with similar threads formed on the adjacent end of the body member 1. The nozzle member 13 is formed with an axial tapered passage 14 the wall of which surrounds and is spaced from the surface of the truncated conical projection 12 so that an annular discharge or exit nozzle 15 is presented by the member 13. An exit passage 16 for the liquid fuel is formed axially through the truncated conical projection 12 in alignment with the exit end 3' of the bore of the member 1, the adjacent ends of the axial passages 16 and 3' in the truncated cone 12 and body member 1 respectively being in register. Through the disc member 11 a plurality of spaced holes 17 are formed.

When the holes 17 are angled all in one direction there is imparted to the pressure fluid passing therethrough a whirling movement round the truncated cone 12.

In operation liquid fuel enters the bore or passage 3, 3' and is discharged from the exit end 16 of the passage in the truncated cone 12 and atomizing pressure fluid passes from the passage 2, 2' into the annular recess or chamber 9. From said chamber 9 the said pressure fluid passes through the holes 17 in the disc member 11 into the space 15 between the surfaces of the

truncated cone 12 and the passage 14 and is discharged around the liquid fuel issuing from the exit end of the axial passage 16 through the truncated cone 12.

- 5 Desirably there is carried by the discharge end of the body member 1 a shield or air deflector 18 of flaring formation adapted to shield, from the direct action of the secondary air supply, the mixture of atomized fuel and atomizing fluid discharged from the member 13. The shield 18 may be formed with a hub portion 18' which sleeves the end of the body member 1 and may be axially adjustable thereon.
- 10

If desired a portion of the flaring shield 18 may be cut away to present a sight opening or the said shield may be formed with a sight hole 19 in register with a sight hole provided in the furnace front.

We claim:—

- 20 1. An atomizer for liquid fuel and the like comprising a tubular body member, a nozzle member having an axial truncated conical passage, an atomizer tip member constituted by a disc having a tubular truncated cone which projects axially from said disc and is positioned within the passage of the nozzle member so as to present an annular discharge passage around said cone, an annular chamber behind said disc, a passage in the body member for conducting atomizing pressure fluid to said annular chamber, and inclined holes, circular in cross section, formed through the disc, the inclination of the holes being the same as the inclination of the truncated cone whereby atomizing pressure fluid is passed from
- 25
- 30

the annular chamber behind the disc through the space around the cone without radial deflection through the disc whereby atomizing pressure fluid is conducted from said annular chamber to the annular discharge passage in the nozzle member.

- 5 2. An atomizer for liquid fuel and the like comprising a body member formed with a bore presenting a liquid fuel passage, a nozzle member having an axial truncated conical passage, a 10 recess formed in the end face of said body member, an atomizer tip member constituted by a disc which is located in said recess and is formed with a tubular truncated cone which projects axially from said disc and is located within the passage 15 of the nozzle member so as to present an annular discharge passage between the outer surface of said cone and the wall of the axial passage of the nozzle member, an annular chamber formed in the body member behind the disc of 20 the atomizer tip member, a passage formed in the annular wall of the body member parallel to the bore thereof and adapted to supply atomizing pressure fluid to said annular chamber, and inclined holes, circular in cross section, formed 25 through the disc, the inclination of the holes being the same as the inclination of the truncated cone whereby atomizing pressure fluid is passed from the annular chamber behind the disc through the space around the cone without radial 30 deflection.
